SIGNAL-LAMP.

1,117,768.

Specification of Letters Patent.

Patented Nov. 17, 1914.

Application filed August 7, 1911. Serial No. 642,779.

To all whom it may concern:

Be it known that we, CARL H. BISSELL and ARTHUR E. VIEAU, citizens of the United States, of Syracuse, in the county 5 of Onondaga and State of New York, have invented a certain new and useful Signal Lamp, of which the following is a specification.

Our invention has for its object the production of a signal lamp and particularly to constructions by which the lens or globe is supported and by which the lamp within the lens or globe can be removed without disturbing the lens; and it consists in the 15 combinations and constructions hereinafter set forth and claimed.

In describing this invention reference is had to the accompanying drawing in which like characters designate corresponding 20 parts in all the views.

Figure 1 is an elevation partly in section of a preferable form of this signal lamp. Fig. 2 is an inverted view of parts seen in Fig. 1.

25 This lamp comprises, generally, a cap, a base, a cylindrical signal lens interposed between the cap and the base, and means for clamping the cap and the base toward each other and thereby holding the lens in position.

1 is the cap which may be of any desirable form size and construction and is here shown as provided with an internally threaded nipple 2 by which a conduit 3 for 35 inclosing electric wires, is attached to the cap. The cap may also be provided with a suitable incandescent electric lamp socket 4 for supporting an incandescent electric lamp 5 as indicated in dotted lines.

40 6 and 7 are respectively sections of the base, and 8 is the lens interposed between the cap and the base, the cap being provided with a seat 9 for the upper edge of the lens 8 and one of the 45 sections as the section 6 of the base being also provided with a seat 10 for the lower edge of the lens, suitable packing rings 11 being interposed between the upper and lower edges of the lens and the seats 9, 10.

50 The section 6 of the base is here shown as in the form of a ring having a flange 12 on its upper face extending into the lens and having an annular groove 13 on its lower face.

The section 7 is discoidal in form and 55 serves as a bottom for the lamp, and bears against the ring 6. Said section 7 is formed with an upwardly extending annular flange 14 for entering the groove 13 and bearing 60 against the bottom thereof.

The means for clamping the base and cap toward each other comprises parts for clamping the cap and the section 6 of the base, and parts for clamping the cap and the section 7 of the base. As here shown the 65 clamping means comprises rods 15 located diametrically opposite each other and pivoted at their upper ends at 16 to the cap and having their lower ends threaded and movable through the open ends of external, 70 diametrically disposed slots 17 in outwardly projecting ears 18 on the ring 6, and nuts 19 turning on the threaded ends of the rods against the under faces of such ears 18; and such clamping means also includes additional rods 20 similar to the rods 15 and pivoted at 21 at their upper ends to the cap and having their lower ends threaded and movable through diametrically disposed 75 open ended external slots 22 provided in 80 ears 23 on the section 7, and nuts 24 screwing on the threaded ends of said rods 20 against the under faces of the ears 23. The ears 23 are located substantially midway between the ears 18.

Owing to the arrangement of the clamping sections 6 and 7 with respect to the lens 8, the section 7 of the base can be readily removed to replace a burned out incandescent lamp without removing the lens, and 90 when desirable the lens can be readily removed.

What we claim is:

1. A lamp comprising a cap, a base, a hollow body interposed between the cap and the 95 base, the base comprising upper and lower sections, one bearing against the body and the other against the section which bears against the body, means for clamping the upper section against the body and coacting 100 therewith at opposite points on the section, and means for clamping the lower section against the upper, the last-mentioned means coacting with its lower section at points between the points of engagement of the 105 first clamping means and the upper section, substantially as and for the purpose described.

2. A clamp comprising a cap, a base, a hollow body interposed between the cap and the base, the base comprising upper and lower sections, one bearing against the body and the other against the section which bears against the body, and means for clamping the lower section in position against the upper section, substantially as and for the purpose specified.
3. A lamp comprising a cap, a base, a hollow body interposed between the cap and the base, the base comprising upper and lower sections, one bearing against the body and the other against the section which bears against the body, and means for clamping each section independently of the other section toward the cap, substantially as and for the purpose set forth.
4. A lamp comprising a cap, a base, a hollow body interposed between the cap and the base, the base comprising two sections, one bearing against the body and the other against the section which bears against the body, and means for clamping and supporting the inner section in position, and additional means for clamping and supporting the outer section, substantially as and for the purpose described.
5. A signal lamp comprising a cap, a base, a lens cylindrical in general outline interposed between the cap and the base, the base comprising two sections, one bearing against the lens and the other against the section which bears against the lens, means for clamping the cap and one of said sections toward each other, and means for clamping the cap and the other of the sections of the base toward each other, substantially as and for the purpose set forth.
6. A signal lamp comprising a cap, a base, a lens cylindrical in general outline interposed between the cap and the base, the base comprising two sections, one bearing against the lens and the other against the section which bears against the lens, and means for clamping the cap and one section of the base toward each other, said means engaging said section at diametrically opposite points, and means for clamping the cap and the other section of the base toward each other, the last-mentioned means also engaging the last-mentioned section at diametrically opposite points located midway between the first-mentioned clamping means, substantially as and for the purpose described.
7. A lamp comprising a cap, a base, a hollow body interposed between the cap and the base and comprising two sections, one a ring having a seat for the body and the other a discoidal shaped part lying against the ring, and means for clamping the discoidal shaped part and the cap toward each other, substantially as and for the purpose described.
8. A signal lamp comprising a cap, a base, a lens cylindrical in general outline interposed between the cap and the base, the base comprising two sections, one a ring having a seat for the lens, and the other a discoidal shaped part bearing against the ring, means for clamping the ring and cap together, and means for clamping the discoidal shaped part and the cap together, substantially as and for the purpose specified.
9. A signal lamp comprising a cap, a base, a lens cylindrical in general outline interposed between the cap and the base, the base comprising two sections, one section comprising a ring having a seat for the lens on one face thereof, and an annular groove on the opposite face thereof, and the other section comprising a discoidal shaped part having an annular flange for entering the groove of the ring and bearing against the bottom thereof, and means for clamping the discoidal shaped part and the cap together, substantially as and for the purpose set forth.
10. A signal lamp comprising a cap, a base, a lens cylindrical in general outline interposed between the cap and the base, the base comprising two sections, one section comprising a ring having a seat for the lens on one face thereof, and an annular groove on the opposite face thereof, and the other section comprising a discoidal shaped part having an annular flange for entering the groove of the ring and bearing against the bottom thereof, means for clamping the ring and cap toward each other, and means for clamping the discoidal shaped part and the cap toward each other, substantially as and for the purpose described.
11. A signal lamp comprising a cap, a base, a lens cylindrical in general outline interposed between the cap and the base, the base comprising two sections, one a ring having a seat for the lens, and the other a discoidal shaped part bearing against the ring, diametrically disposed means for clamping the cap and the discoidal shaped part toward each other, and diametrically disposed means located midway between the first-mentioned means for clamping the cap and ring toward each other, substantially as and for the purpose specified.
12. A signal lamp comprising a cap, a base, a lens cylindrical in general outline interposed between the cap and the base, the base comprising two sections, one a ring having a seat for the lens, and external slots located diametrically opposite each other, each slot being open at one end, and the other section comprising a discoidal shaped part bearing against the ring and formed with external slots, each of which is open at one end, the slots of one section being located midway between the slots of the other.

section, and clamping means comprising rods pivotally connected to the cap at corresponding ends and having their other ends threaded and movable into the slots, and nuts screwing on such other ends, substantially as and for the purpose set forth.

In testimony whereof, we have hereunto signed our names in the presence of two

attesting witnesses, at Syracuse, in the county of Onondaga, in the State of New York, this 28th day of July 1911.

CARL H. BISSELL.
